(57) CLAIM

The ornamental design for a razor package, as shown and described.

DESCRIPTION

FIG. 1 is a perspective view of a razor package of the present invention;

FIG. 2 is a front view thereof;

FIG. 3 is a perspective view of a design for a razor package according to a second embodiment of the present invention;

FIG. 4 is a front view thereof;

FIG. 5 is a perspective view of a design for a razor package according to a third embodiment of the present invention; and,

FIG. 6 is a front view thereof.

The claim is limited to the elements shown in solid lines in the drawings.

Further, the broken lines are environmental subject matter shown for illustrative purposes only and form no part of the claimed design.

1 Claim, 6 Drawing Sheets
